UNITED STATES PATENT OFFICE.

CHARLES RUDOLF, OF CHICAGO, ILLINOIS.

WINDOW-CLEANING DEVICE.

1,167,935.

Specification of Letters Patent. Patented Jan. 11, 1916.

Application filed May 1, 1915. Serial No. 25,163.

To all whom it may concern:

Be it known that I, CHARLES RUDOLF, a citizen of the United States, residing at Chicago, in the county of Cook and State of Illinois, have invented a new and useful Improvement in Window-Cleaning Devices, of which the following is a specification.

This invention relates particularly to window-cleaning devices adapted to the purpose of simultaneously cleaning both sides of a window. Such a device is particularly useful for cleaning windows of office buildings, or the like, inasmuch as it can be used without endangering the life or limb of the operator.

The primary object is to provide a window-cleaning device which will operate effectively to clean both sides of a window, and which shall be of simple, cheap and durable construction.

The invention is illustrated in its preferred embodiment in the accompanying drawings, in which—

Figure 1 represents a broken sectional view of a window with my improved window-cleaning device mounted for cleaning the window; Fig. 2, an enlarged broken sectional view taken parallel with the section shown in Fig. 1; Fig. 3, a horizontal sectional view taken approximately as indicated at line 3 of Fig. 2; Fig. 4, a sectional view taken as indicated at line 4 of Fig. 2; Figs. 5 and 6, broken sectional views taken as indicated at the corresponding lines of Fig. 2; Fig. 7, a broken sectional view showing the construction of one of the elbows; Fig. 8, a broken view illustrating the manner in which the cleaning tool is applied to each forearm of the device; and Fig. 9, a section taken as indicated at line 9 of Fig. 8.

In the preferred construction, which is illustrated, A represents a base-plate adapted to lie across a window-sill and be adjustably secured thereto; B, a mounting adjustable longitudinally in the plate A and equipped with rock-shaft bearings B¹ and sash-supports B²; C, a large tubular rock-shaft rotatable in the bearings B¹; D, D a pair of lower or main arms connected by pivots, or shafts, 1 to bearings, with which the end-portions of the tubular rock-shaft C are equipped; E, E a pair of upper or fore-arms forming elbows with the arms D, with which they are connected by pivots 2; F, F wiping devices, or tools, of any suitable character, pivotally and detachably carried by

the upper ends of the arms E, E; G, G racks, or rack-equipped slides mounted in the arms D, which are preferably tubular, and having their upper ends engaging gear-segments 3, 60 with which the lower ends of the arms E are equipped, and having their lower ends engaging gears 4 mounted on the shafts 1; G¹ a rack slidable through the tubular rock-shaft C, and meshing at one end with one of the gears 4, and at the other end with an idler-gear 5, which meshes with the other gear 4; and H, H a pair of racks slidable through the rock-shaft C and meshing at one end with gear-segments 6, with which 70 the lower end of one of the arms D is equipped, and meshing at the other end with idler-gears 7, which, in turn, mesh with the gear-segment 6, with which the base-portion 75 of the other arm D is equipped.

The construction is such that the arms D have universal connection, through the medium of the pivots 1 and the tubular rock-shaft C, with the mounting B; also, such that the movements of one arm D are duplicated by the other arm D, and the movements of one arm E are duplicated by the other arm E.

K represents the window-frame, which is equipped with a sill-plate 8; and K¹ represents the window-sash carrying the glass K².

The base-plate, or sill-carried plate A, is provided with a guide 9, on which the base-portion of the mounting B is longitudinally adjustable, said mounting being secured, 90 when adjusted in the guide 9, by a set-screw 10. The member A has one end provided with a bracket 11 having a clamping-screw 12, for engaging the inner edge of the ledge of the window-sill, and having a clamping-screw 13 for engaging the lower margin of the ledge of the window-sill. The body of the member A is equipped with a lug 14, which carries a clamping screw 15 adapted to engage the outer edge of the top member of the window-sill 8, as shown in Fig. 1. The outer end of the member A is equipped with a set-screw 16, whose lower end is adapted to bear on the outer portion of the window-sill.

The bearings B¹, which flank the sash-supports B², are provided with suitable bores to receive and permit rotation of the tubular rock-shaft C. One of the bearings B¹ is provided with a circumferential slot 110 17, in which works a stud 18 carried by the rock-shaft C, thus limiting the rotation of

the rock-shaft in its bearings. The rock-shaft is free to turn, however, sufficiently to permit the tools F to swing downwardly to the plane, or below the plane, of the rock shaft. The sash-supports B², which are on opposite sides of the rock-shaft C, are recessed at their upper ends to accommodate the lower edge portion of the sash K¹.

The tubular rock-shaft C contains in its lower portion an insert, or fillet, C², which is provided with guides for the rack G¹ and the racks H, H. The member C² is provided at each end with a pair of bearings 19, 19 and a pair of bearings 20, 20, through which the shafts, or pivots, 1, extend; and at one end of the rock-shaft said bearings support the pins, or shafts, 21 and 22, on which the idlers 5 and 7 are mounted, respectively.

The racks G, G are suitably mounted to slide in the tubular arms D, D. One of the arms E is equipped near its upper end with a knob, or handle, 23, by means of which the device may be operated.

As will be understood from Figs. 8 and 9, each tool, or wiper, F (which may comprise a sponge, mop or squeegee) has or includes a plate 24, which is detachably mounted on lugs 25, with which the upper end of the arm E is equipped. In the illustration given, the plate 24 has its outer or back surface equipped with lugs 26, one of which has a stub-pivot 26^a entering the adjacent pivot-lug 25 of the arm E; and the pivot connection at the other lug 25 is provided by the spring-projected plunger 27 equipped with a thumb-piece 28. The thumb-piece 28 is disposed opposite a finger-piece 29 carried by the lug 26, which carries the stub-pivot 26^a. By the means described, the tool F may be removed at will from the arm E, and another tool substituted, or a fresh cloth, or wiping portion, applied, as the case may be.

In the use of the improved device, the clamping-plate A is securely clamped to the window-sill, and the sash is lowered to rest upon the sash-supports B², the mounting B being suitably adjusted in the clamping-plate A. The operator then, through the medium of the handle 23, actuates the arm E, which is inside of the window, thus moving the corresponding tool over the inner surface of the glass in any desired direction. The movements of the actuated arm E are communicated through the corresponding rack G, the rack G¹ and the other rack G, to the duplicate arm E; and the movements of the arm which is near the operator, are communicated through the rack G¹, to the other arm D. Thus, the tools F are given corresponding movements, and both the inner and outer surfaces of the window are cleaned.

The device described is simple, easily operated, and the tools or wiping devices are capable of a large range of movement.

The foregoing detailed description has been given for clearness of understanding only, and no unnecessary limitation should be understood therefrom, but the appended claims should be construed as broadly as 70 permissible, in view of the prior art.

What I claim as new, and desire to secure by Letters Patent, is—

4. In a window-cleaning device, the combination with a suitable support adapted to be carried by a window-sill, of a rock-member mounted thereon, a jointed arm carried by each end of said rock-member and flexing in a plane perpendicular to the window, a cleaning tool carried by each jointed arm, and motion transmitting mechanism connected with the upper sections of the jointed arms and extending through the lower arms and through said rock-member, whereby the swinging movement of one upper arm-section about its lower arm-section is duplicated by the upper arm-section on the opposite side of the window.

5. In a window-cleaning device, the combination of a base-member adapted to be mounted on a window-sill, a sash-support and a rock-shaft supported thereby, a pair of jointed arms carried by said rock-shaft and flexing in a plane perpendicular to the window, and motion transmitting mechanism connecting the upper arm-sections and extending through said rock-shaft.

6. In a window-cleaning device, the combination of a base-member equipped with clamping means, a rock-shaft carried thereby, a pair of lower arms having pivotal connection with the rock-shaft, of such a character as to enable the rock-shaft to be rotated through the medium thereof, mechanism connecting the base-portions of said arms, whereby the swinging movement of one arm about its pivot is duplicated by the other arm, a pair of upper arms pivotally connected with said first-named arms, and connecting mechanism between the base-portion of the upper arms, said mechanism extending through the lower arms and through said rock-shaft, whereby the swinging movement of one upper arm about its pivot is transmitted to the other upper arm.

7. In a window-cleaning device, the combination with a suitable mounting, of a rock-shaft journaled therein, a pair of lower arms pivotally connected with the ends of said rock-shaft and equipped with gear-sectors, rack connections between said gear-sectors slidably connected with said rock-shaft, a pair of upper arms pivotally connected with the lower arms and equipped with gear-sectors, racks extending through the lower arms and engaging said last-named gear-sectors, and gear and rack connections between the lower ends of said last-named racks and mounted on said rock-shaft.

5. In a window-cleaning device, the combination of a suitable mounting adapted to be carried by a window-sill, a tubular rock-shaft journaled therein, a pair of lower arms 5 pivotally connected with said rock-shaft and equipped with gear-sectors, a rack slidably mounted in said rock-shaft and serving to transmit motion from one of said gear-sectors to the other, a pair of racks slidably 10 connected with said arms, gear and rack connections mounted in the rock-shaft and connected with said last-named racks, a pair of upper arms equipped with gear-sectors engaging the racks with which said lower 15 arms are equipped, and cleaning tools mounted on said upper arms.

6. In a window-cleaning device, the combination of a base-plate equipped with clamping means for securing it to a window-sill, a mounting adjustably carried by said base-plate and equipped with a sash-support, a rock-shaft journaled in said mounting, joined arms mounted on said rock-shaft, cleaning tools carried by said jointed 25 arms, and connecting mechanism between, the arms extending through the rock-shaft.

7. In a window-cleaning device, the combination of a base-plate equipped with means for securing it on a window-sill, a mounting adjustably connected with said base-plate, a sash-support carried by said mounting, a tubular rock-shaft carried by said mounting, lower arms pivotally connected with said rock-shaft and equipped with 30 gear-sectors, pinion and rack connections mounted in the rock-shaft and connected with said gear-sectors, racks slidably connected with said arms, pinion and rack connections mounted in the rock-shaft and connected with said last-named racks, upper 35 arms pivotally connected with said first-named arms and equipped with gear-sectors meshing with the racks with which the lower arms are equipped, and cleaning tools carried by said upper arms.

8. In a window-cleaning device, the combination of a base-plate equipped with means for securing it on a window-sill, a mounting adjustably connected with said base-plate, a sash-support carried by said mounting, a tubular rock-shaft carried by said mounting, lower arms pivotally connected with said rock-shaft and equipped 50

with gear-sectors, pinion and rack connections mounted in the rock-shaft and connected with said gear-sectors, racks slidably connected with said arms, pinion and rack connections mounted in the rock-shaft and connected with said last-named racks, upper arms pivotally connected with said first-named arms and equipped with gear-sectors meshing with the racks with which the lower arms are equipped, and cleaning tools detachably mounted on the free extremities of the upper arms. 65

9. In a window-cleaning device, the combination of a suitable mounting, a tubular rock-shaft mounted therein and having its lower portion equipped with rack-guides, racks mounted in said guides, a pair of lower 70 arms pivotally connected with said shaft and equipped with gear-sectors, one of which meshes with one of said racks, an idler interposed between the other gear-segment and the same rack, a pair of gears journaled coaxially with the pivots of said arms, one of which meshes with another of said racks, an idler interposed between the rack last referred to and the other gear, a pair of racks slidably connected with said arms and meshing with said gears, a pair of arms pivotally connected with said first-named arms and equipped with gear-sectors meshing with said last-named racks, and cleaning tools carried by the free ends of said last-named 75 arms. 80

10. In a window-cleaning device, the combination of a suitable mounting equipped with a sash-support, a tubular rock-shaft journaled in said mounting and equipped with racks slidable through the rock-shaft, a pair of tubular lower arms pivotally connected with the rock-shaft and having gear-connections with one of said racks, a pair of racks slidable through said tubular arms 90 and geared to another of said first-named racks, a pair of upper arms pivotally connected with said first-named arms and equipped with gear-segments meshing with said last-named racks, and cleaning tools 95 movably mounted on said upper arms. 100

CHARLES RUDOLF.
